UNITED STATES PATENT OFFICE.

WILLIAM JOHN RICKETS, OF LONDON, ENGLAND.

CONTROLLING AND REGULATING SYSTEM FOR DYNAMOS.

Application filed May 21, 1920. Serial No. 383,194.

To all whom it may concern:

Be it known that I, WILLIAM JOHN RICKETS, a subject of the King of Great Britain, and a resident of London, England, **5** have invented a new and Improved Controlling and Regulating System for Dynamos, of which the following is a full, clear, and exact description.

This invention relates to improvements in **10** regulating systems of the kind described in my previous British provisional specification No. 11,123 of 1919, hereinafter referred to as the former specification.

In this specification electronic or ionized **15** gas valves of the incandescent cathode type are described as being employed as controlling means for use with variable speed dynamos, for regulating the voltage and the charging or output current of such dynamos.

20 In the practical use of such devices certain difficulties and limitations manifest themselves, and it is the object of the present invention to improve the arrangements described in my former specifications in **25** such manner as to render the apparatus more efficient in action, and of wider applicability.

In the previous arrangements referred to, the cathodic filament or filaments are rendered incandescent by current taken through **30** a resistance or a field winding from the main brushes of the dynamo.

If exact regulation is to be obtained the **35** heating of the filament should be due, predominantly, to this current and not to that flowing from the anode of the valve.

Hence the current flowing from the anode should always be less than that directly supplied to the filament which condition imposes certain limits of design.

40 Again when the valve is used to regulate the flow of charging current passing to an accumulator battery, this current is also limited by the carrying capacity of the cathodic filament.

45 If this filament is increased in cross-section, to carry more current, and is heated by the main field current, or by current passing through a resistance and flowing under the full output volts, the loss in such a resistance or in the main field winding becomes great for a large current carrying capacity of valve, and the efficiency of the whole system is lowered.

According to the present invention heating of the filamental cathode of the valve **55** is effected by current generated in a closed

loop circuit including the filament, one point of which circuit is connected to the negative pole or brush of the generator.

This loop circuit may be of low resistance **60** and the filament may have large current-carrying capacity whilst requiring a relatively small wattage for heating.

As the filaments so proportioned and disposed can be of considerable cross-section **65** and therefore will not be liable to become excessively heated by anodic current they are especially useful in controlling the battery current in the manner set forth in my other application above referred to, by the **70** use of a bi-anodal valve or two valves and the resistance system as shown in Figure 4 of that specification.

The voltage acting in the loop circuit is **75** so produced that it is, at all times, a function of the field strength and speed of the machine.

The incandescence of the filament therefore varies with the output voltage and hence regulation of this voltage is obtained in the **80** manner set forth in the said specification.

For the better explanation of the invention reference is made to the appended drawings, Figures 1 to 8.

Of these Figures 1 and 2 represent the **85** application of the valve tube as a regulator for a dynamo.

Figure 3 is a modification of Figure 1 of this specification illustrating means by which voltage regulation of large generators **90** can be conveniently obtained with small excitation losses.

Figures 4, 5, and 6 represent diagrammatically alternative methods of heating the **95** filaments.

Figure 7 represents another arrangement for using a valve as regulator in the manner set forth.

Figure 8 relates to the disposition of a **100** switch for allowing reversed rotation of the machine.

Referring to Figure 1 of the present specification a direct current ring, drum or like armature 1 having brushes 2 and 3 is connected with a shunt field winding 5 and a **105** differential winding 13.

The winding 5 may be connected to the two brushes directly or, as shown, through the cathodic filament 6 of the valve 7.

The armature 1 is provided with a winding of known type generating continuous current and also has an electrically inde-

pendent winding generating alternating current connected to the slip rings 8 and 9 associated with brushes 10 and 11 connected to the filament 6, the whole circuit constituting a closed loop which is connected to the negative pole or brush 2.

The anodic plate, sheath or like electrode 12 is connected to the winding 13 which is magnetically opposed to the shunt field winding 5.

The operation of the system thus arranged is as follows:

The direct current voltage generated in armature winding 1 always bears a definite ratio to the effective alternating voltage applied to the filament 6.

Hence as a certain predetermined voltage is approached the filament 6 becomes incandescent and the consequent increase in the valve conductivity allows current to flow through the counterwinding 13 limiting the possible voltage rise of the system.

The negative pole of the battery may be connected to the anode 16 by means of the switch arm 18, which in this case will rest on a contact 19. As arranged in Figure 1, part of the counter winding functions as a series winding, employing the dynamo as a motor for starting any mechanically connected prime mover or alternatively a separate series winding may be employed for the purpose in which case the connections will be as shown in dotted lines.

By these arrangements the battery is normally prevented from discharging through the armature circuit, but when the cathode filament becomes incandescent at the appropriate voltage, the dynamo will charge the battery over the following circuit: terminal 3 of the dynamo, winding 13, wire 23, battery 14, switch arm 18, contact 19, over the wire to anode 16, filament 6, and thence to terminal 2 of the dynamo.

Leads 23 and 24 as shown in the figures carry the output current to consuming circuits.

Figure 2 shows a second method of connecting the shunt winding 5 in which this winding is in series with a ballast resistance 25, the junction of this resistance and field winding being connected to the anode 12 of valve 7 in which a second battery charging anode 16 may be arranged as before.

This arrangement functions by diverting current from the field winding, when the valve conductivity increases, thus reducing the excitation as the predetermined voltage is approached.

Figure 3 illustrates a method whereby the voltages of dynamos of large output may be positively and practically limited with small excitation losses.

This arrangement comprises the larger capacity output generator A and a smaller

capacity counterboosting generator B, these generators being mechanically coupled together.

The main generator armature has a separate alternating current winding and slip rings 8 and 9.

The slip rings are connected as in Figure 1 to a valve cathode filament 6 and the heating loop so constituted is as before connected to the negative pole 2 of the main generator. The anode of the valve is connected through the booster field winding 26 to the positive pole of the main generator A. The counter booster armature 27 is connected in series with the main generator shunt field winding 28 across the positive and negative poles of the main generator.

The valve 7, the winding 26, and armature 27 may be of comparatively small current carrying capacity. As the speed of the coupled machines rises the voltage generated in the alternating winding of armature 1 increases and the filament 6 becomes heated. Beyond a certain determinate speed any slight increase causes a greatly increased conductivity of valve 6. Up to this speed the counter booster generator B remains practically unexcited and a powerful current flows in field winding 28 of the main generator which is consequently strongly excited and giving its maximum voltage.

A very slight increment of speed acting as shown allows current to flow through the counter boosting field winding when the armature 27 yields a greatly increased voltage opposed to the main voltage.

Hence the field excitation of the main generator falls as the speed increases maintaining a virtually constant voltage with small excitation losses.

This arrangement is very suitable for the practical application of the system to large generators in which the losses in ballast resistances, valve excitations or in differential windings are not negligible.

Figure 4 shows an alternative method of connecting the cathode filament, namely to the secondary winding 29 of a transformer the primary winding 30 of which is fed by pulsating current passing from the intermediate brush 31 to brush 2.

The brush 31 bears upon the single slip ring 32 which in this modification is connected to one point on the peripheral conductors of armature 1 or to equipotential points if the said armature is multipolar.

The potential of ring 32 thus connected varies cyclically from that of the pole 3 to that of pole 2, and this pulsation of potential gives rise to alternating currents through filament 6 which increase with the speed of the machine.

The points on the armature winding of maximum potential difference may be connected to two slip rings and the trans-

former winding 30 may be connected across such slip rings.

Figure 5 indicates another modified low pressure supply to the loop circuit.

5 The loop including brush 2, part of the winding of armature 1, brush 33 and the filament carries a comparatively large current at a low voltage. The armature in this case co-acts with three brushes 2, 3, 10 and 33.

The relative circumferential displacement of brushes 2 and 33 may be only a few electrical degrees and the voltage between them low.

15 Figure 6 indicates a modified form of loop circuit supplied by alternating current in which three slip rings 34, 35, and 36 are used in connection with a winding 37 arranged on armature 1. In this arrangement 20 the middle point of the winding connects the slip ring 35 on which brush 38 bears. This brush is directly connected to pole 2, the other two brushes 39 and 40 connecting the terminations of winding 37 25 to the filament 6. By this method the control current from the anode flows first through one limb of the filament and then through the other limb alternately causing a very equitable heating effect.

30 Figure 7 shows a further arrangement in which a single field winding 41 and a resistance 42 is used. The field winding is connected from a mid-potential brush 43 to one termination 44 of the resistance 35 42 the other termination of which connects directly to pole 3.

The point 44 is connected to the anode 12 directly or through a resistance 45. The cathode is connected to pole 2 and may be 40 excited by any of the means herein described, although the arrangement employed in Figure 1 is shown.

45 When the machine is running at and above a predetermined speed the resistance of valve 6 falls and the potential of the point 44 more and more closely approximates to that of mid-potential brush 43, hence the current through field winding 41 declines, the output voltage remaining practically steady.

50 When the machine is attached to a prime mover which may not only vary in speed but may rotate in one direction and sometimes in the opposite sense, the dynamo 55 brushes may be connected to the rest of the apparatus as herein set forth through a change-over switch 46 which is automatically thrown over in any known manner when the rotation of the armature is reversed.

In such case, the mid-potential brush 43, if such is employed, need only have a fixed 65 connection to winding 41 of Figure 7. When the switch is so employed the system here set forth may be more readily used for

train lighting or in boats, such for example as ferry boats, driven by reversible and variable speed prime movers.

The controlling and regulating valves, owing to their filaments becoming more or less incandescent when the machines are at operative speeds, may be used as indicating lamps and may be mounted in guard casings in the vicinity of the persons supervising the working of the system. 75

It is sometimes preferable to employ pilot lamps as signals carrying all or part of the current taken through the valve filament, these lamps being singly or in parallel with resistance, connected in series 80 with the cathodic filaments, cease to glow if such filaments become ruptured.

As the current distribution in the cathode filaments is not uniform owing to the flow of thermionic current from the anode it is 85 preferable to use a filament of varying cross section, the section of each element of the cathode being proportioned to the current flowing across the section in such manner that no excessive heating of any particular element of the filament shall take place. Such non-uniform filaments can be obtained by electro-chemical or chemical solution of a portion of the filament or by mechanical 90 means. 95

The dynamo when arranged to operate the valve filaments on alternating current may be so constructed as to deliver a certain amount of such alternating current to an 100 outside circuit, as will be readily understood by those versed in the art, without further explanation.

Various slight changes might be made in the general form of the parts described without departing from my invention, and hence I do not limit myself to the precise details set forth, but consider myself at liberty to make such slight changes and alterations as fairly fall within the spirit and scope of the appended claims. 110

1 claim:—

1. The combination with a dynamo electric machine, of a valve having a filament therein affected by current generated by said machine in a closed loop circuit including the filament one point of which circuit is connected to the negative pole of the dynamo. 115

2. The combination with a dynamo electric machine, of a thermionic means having a filament and generating means for producing current in response to the movement of the dynamo, said generating means and the filament of the thermionic means being disposed in a closed loop circuit, one point of which circuit is connected to the negative pole of the dynamo. 120

3. In a device of the character described comprising a dynamo electric machine, a valve having a filament therein affected by 130

current generated by said machine in a closed loop circuit including the filament, one point of which circuit is connected to the negative pole of the dynamo, and controlling the voltage of said dynamo electric machine.

4. The combination of a generator having a shunt field, a differential winding, a thermionic means including a uni-laterally conductive valve tube of the incandescent cathode type having a filament therein affected by current generated by said machine in a closed loop circuit including the filament, one point of which circuit is connected to the negative pole of the dynamo, the anodic plate of the valve being connected in a circuit with the differential winding, whereby at a predetermined speed, an increase of current will be effective through the differential winding to maintain a relatively constant voltage of the generator.

5. An electrical apparatus comprising a dynamo, an armature winding therefor, a differential winding, thermionic means having a filament therein affected by current, a closed loop circuit in which said filament is disposed, a connection between one part of said circuit and the negative pole of the dynamo, and a connection between another part of said circuit and the differential winding.

6. In a dynamo electric machine comprising an armature, a field winding therefor, a counter field, a thermionic means having a filament therein affected by current generated by said machine in a closed loop circuit including the filament, one point of which circuit is connected to the negative pole of the dynamo and having an incandescent cathode and an anodic plate connected respectively with said windings, for effecting voltage control of the said dynamo electric machine.
